UNITED STATES PATENT OFFICE.

DANIEL MCFARLAN MOORE, OF NEWARK, NEW JERSEY, ASSIGNOR TO THE
MOORE ELECTRICAL COMPANY, OF NEW YORK, N. Y.

AUTOMATIC VIBRATORY INTERRUPTER.

SPECIFICATION forming part of Letters Patent No. 604,684, dated May 24, 1898.

Application filed December 17, 1896. Serial No. 615,971. (No model.)

To all whom it may concern:

Be it known that I, DANIEL MCFARLAN MOORE, a citizen of the United States, and a resident of Newark, in the county of Essex and State of New Jersey, have invented a certain new and useful Automatic Vibratory Interrupter, of which the following is a specification.

My invention relates to automatic circuit-interrupters of the vibratory type, and is designed more particularly to improve upon interrupters of the class wherein the action is produced by an electromagnet the circuit of which is broken at each vibration.

15 The object of the invention is to insure the continued action of the interrupter whenever from any imperfection of its contacts or from other cause the device comes to a rest; and the invention consists in the combination, with 20 the interrupter, of a jarring device which acts to cause the interrupter to shake or tremble and to thereby resume its action. This jarring device is preferably in the form of a knocker, striker, or hammer which is caused 25 to impinge upon the interrupter or the support therefor either at periodically-recurring intervals of greater or less duration, as desired, or is by some controlling device brought into action only when occasion demands, as 30 when the automatic interrupter ceases or deviates from its normal action. This controlling device may be a sluggish electromagnet connected into the circuit of the interrupter and adjusted as to sluggishness so as not to 35 respond to the interrupter, but to act when the interrupter comes to rest, and thereby prolongs or continues the flow of current over the interrupter-contacts or otherwise deviates from its normal action, so as to permit the 40 passage of an abnormal current. Conveniently the magnet may serve as an actuating-magnet to lift or draw back the striker for its blow, and when so used it may by combination with a suitable circuit-breaker be 45 made to have an automatic vibratory movement, so as to vibrate the striker and cause its blows to be repeated.

My invention is intended primarily for application to automatic interrupters for cir-

cuits of self-induction whose discharges are 50 employed for producing luminous or other peculiar effects, as described in my prior patents, Nos. 548,576 and 548,127; and the present invention consists, further, in the combination, with said circuit, of means for giving 55 self-induction to the circuit placed on both sides of the break at the interrupter instead of on one side only, as shown in said patents. Ordinarily coils organized to give high self-induction may be used for this purpose. The 60 second self-induction coil may conveniently be the coil of the magnet before referred to which operates with the striker or knocker; but other coils may be used for the purpose, and generally will produce better effects if 65 constructed for rapid discharge.

The invention consists also in certain improvements in vibratory interrupters whereby a more steady and rapid action may be secured.

The invention consists, further, in the combinations of apparatus specifically herein-after claimed.

In the accompanying drawings, Figure 1 is a general diagram of apparatus embodying 75 my invention. Fig. 2 is a modification in the manner of controlling the action of the jarring device. Fig. 3 is a further modification.

Referring to Fig. 1, a is a circuit to be rapidly interrupted, and B is the interrupter-lever, included, with its back contact, as shown, in said circuit. The interrupter is kept in vibration by an electromagnet C, also in said circuit and acting in obvious and well-known manner. Preferably the core of magnet C is 85 laminated or made of a bundle of iron wires. Said magnet may serve to give self-induction to the circuit interrupted, and its discharge may be delivered to a circuit b, connected to opposite sides of the break produced by the 90 interrupter for the production directly or indirectly of luminous effects in a vacuum-tube or for other purposes. This interrupter-lever B is what I term a "balance-lever" and is pivoted at or near its center of gravity, so 95 as to be capable of movement on its fulcrum, free from any tendency to pendulous or other action and effects of inertia or momentum,

being thereby left perfectly free to take on such vibration as may be imparted to it by the intermittent action of the magnet or magnets which operate upon it. As a retractor for 5 such lever acting in opposition to magnet C, I employ electromagnet D by preference, which magnet is energized from the circuit *a* or otherwise and preferably exerts a constant pull tending to cause the vibrator to close the 10 circuit. By this organization I am enabled to secure an exceedingly rapid action of the interrupter and one well suited for use in systems of lighting wherein the discharges from a circuit of induction which is rapidly interrupted are employed as a means for lighting a vacuum-tube or other device.

The tube inclosing and within which the interrupter is mounted is supported on a stand or clip, as shown.

20 E is a knocker or striker adapted to strike upon and jar the tube, thereby jarring the interrupter and causing it to slightly vibrate or tremble. This knocker may consist of the core of the electromagnet F, which actuates 25 the striker. The end of the core may be armed with leather where it strikes the tube, so as to diminish the chance of breakage, and the electromagnet may draw up the striker for the blow and then release it through in- 30 terruption of its own circuit produced by a circuit-breaker, (indicated at *f*), one member of which is moved by the core away from contact with the opposite member, said circuit-breaker being in and normally completing the 35 circuit of said electromagnet F. By this means the striker will operate as an automatic vibratory striker so long as current suitable for operating the core is continually supplied to said electromagnet. The action of the striker 40 or knocker, however operated, may be controlled by a sluggish magnet in the circuit of the interrupter B and adjusted so as not to respond to the influence of the current when rapidly broken by the interrupter, but to nevertheless act when the interrupter deviates from normal action or stops acting and allows an increase or modification in the flow 45 of current across its contacts. The sluggish magnet may also actuate the striker or jar- 50 ring device, as shown in Fig. 1. When the knocker is used as shown in Fig. 1 or as shown in Fig. 2, the sluggish magnet may bring the knocker into action by closing a circuit to its actuating-magnet E' or to a magnet operating in any other way to bring the 55 knocker or striker into action. The magnet may be made sluggish by using a solid piece of iron for its core or by providing the magnet with an inductive sleeve, band, or circuit 60 of copper or other conductor closed on itself in short circuit or in any other way, as well understood in the art. In Fig. 2 the sluggish magnet F' has an armature which serves, when drawn by the magnet, to close a branch 65 which includes the knocker-magnet E'. The latter in this case actuates its armature to

cause the same to strike and jar the inter- 70 rupter or its support. The interrupter is here shown as of the ordinary spring-mounted type.

The operation of the apparatus is briefly as follows: During normal action of the interrupter B the core E maintains its position, being unadapted to respond to the brief or momentary pulses of current. If the interrupter stops or slows or fails to complete its full vibration, more current flows, and the striker comes into action, jars the interrupter, and starts it into operation again and itself comes to rest. With each interruption the 80 circuit of self-induction discharges into circuit *b* *b*, coils C and F at such time acting in concert to produce the desired effects. This second coil also has a beneficial effect in preventing the extra currents generated by the 85 break from flowing off upon the circuits from which the self-induction circuit takes its current. It is preferably constructed or adjusted so that the self-induction of the circuit at opposite sides of the break shall be practically 90 equal. I find that by equalizing the self-induction at the opposite sides of the break I obviate to a great extent the discharges across the points of the interrupter, which discharge passes across the break as a small arc and 95 produces heating and by electrolytic action produces waste or wear of the contacts. This I find in practice is a very valuable feature, inasmuch as it practically does away with the wear of the contacts and also avoids the dis- 100 sipation across said contacts of the discharge, which would otherwise go to the circuit containing the tube or other device. As already stated, this feature is of value also in preventing the flow over the line of the high-poten- 105 tial energy by choking it back at the instant of interruption.

As indicated in Fig. 3, the magnet of the knocker or striker might be connected into a branch or independent circuit and operate at 110 all times to insure continued action of the interrupter. The striker-magnet may be adjusted to produce a comparatively slow movement of the striker. The action of the interrupter should ordinarily be very rapid.

115 As shown in Fig. 3, an independent electromagnet C² may operate as the second self-induction coil on the opposite side of the break from C. This self-induction coil is constructed for rapidity of charge and discharge. In Fig. 3 the striker engages the base supporting the apparatus.

What I claim as my invention is—

1. The combination in an automatic vibratory interrupter, of an operating-magnet 125 therefor in the circuit including the interrupter-contacts, and a jarring device for insuring continuous action of the interrupter, as and for the purpose described.

2. The combination with an automatic elec- 130 tronagnetic vibratory interrupter, substantially as described, of a striker for jarring the

- contacts, and a separate actuating-magnet for said striker in a circuit controlled by the interrupter.
3. The combination with an automatic vibratory interrupter, substantially as set forth, of a striker, and a sluggish magnet controlling it and energized on the cessation of the interrupter, as and for the purpose described.
4. The combination with an automatic vibratory interrupter, of a striker, and a sluggish actuating-magnet therefor having a self-acting circuit-breaker controlled by the flow of current through the interrupter-contacts, as and for the purpose described.
- 15 5. The combination with an automatic rapidly-operating vibratory interrupter, substantially as described, of a vibratory striker or knocker independently of the vibratory portion of the interrupter, and a magnet in the circuit of the interrupter-contacts for operating it, as and for the purpose described.
- 25 6. The combination with a pivoted vibratory contact, of contacts with which it coöperates to make and break an electric circuit, of a striker for jarring the pivoted contact but without touching it to prevent its sticking to a contact with which it coöperates.
- 30 7. The combination with a vacuous receptacle, of a balanced vibrating contact mounted therein, a contact within said receptacle with which the balanced contact coöperates to make and break circuit, magnets for vibrating the balanced contact, and a striker for jarring the receptacle occasionally to insure 35 the continued operation of the balanced contact.
- 40 8. The combination with a vibrating contact, of magnets alternately energized to produce the vibration of said contact, a striker for jarring the vibrating contact to insure its continuous action, and a magnet for controlling the actions of the striker, said magnet being connected in the circuit controlled by the interrupter and timed to act when the interrupter comes to rest, as and for the purpose set forth.
- 45 9. In a vibratory interrupter, a balanced lever and two magnets operating respectively at opposite sides of the fulcrum of said lever
- one to close and the other to open the circuit, 50 in combination with a circuit controlled by the interrupter and containing means whereby the interrupter is maintained in continuous operation, as and for the purpose described.
- 55 10. The combination with a vacuous receptacle, of a balanced contact mounted therein, a fixed contact sealed in the wall of said receptacle and engaging the balanced contact, and electromagnets arranged exterior to and 60 under opposite ends of the balanced contact for producing a continuous vibration of said contact for the purpose set forth.
11. The combination in an automatic continuously-operating vibratory interrupter 65 having an actuating-magnet in the circuit of the interrupter-contacts, of a retractor-magnet supplied by a branch from the main circuit and acting with a constant retracting power tending to close the circuit to the interrupter.
12. In a vibratory interrupter, a balanced contact-lever, a magnet acting with a constant power upon said lever and tending thereby to maintain it in a certain position, and another 75 magnet in the circuit of the interrupter-contacts and acting intermittently to move said contact-lever from that position for the purpose set forth.
13. The combination with the interrupter, 80 of the circuit of self-induction having two self-inductive coils on opposite sides of the break respectively, and a circuit into which said coils discharge in concert connected to opposite sides of said break.
- 85 14. In an apparatus for producing electric vibrations or disturbances by discharges from a rapidly-interrupted circuit of induction, the combination with an interrupter, of a circuit having its self-induction equalized at opposite 90 sides of the break.

Signed at New York, in the county of New York and State of New York, this 15th day of December, A. D. 1896.
